Patented May 4, 1976

239,755

TACO FORMING TOOL

Larry D. Moore, 122 Broad St.,
Wadsworth, Ohio 44281

Filed Sept. 3, 1974, Ser. No. 502,813

Term of patent 14 years

Int. Cl. D7—04

U.S. Cl. D7—43

FIG. 2

FIG. 1

FIG. 3

FIG. 1 is a side elevational view of a taco forming tool showing my new design;

FIG. 2 is an elevational view thereof as seen from the left of FIG. 1; and

FIG. 3 is an elevational view thereof as seen from the right of FIG. 1.

I claim:

The ornamental design for a taco forming tool, as shown and described.
